UNITED STATES PATENT OFFICE.

DAVID FROEHLICH, OF BROOKLYN, NEW YORK.

AWNING ROLLER.

Application filed December 16, 1922. Serial No. 607,420.

To all whom it may concern:

Be it known that I, DAVID FROEHLICH, a citizen of the United States, and a resident of the city of New York, borough of Brooklyn, in the county of Kings and State of New York, have invented a new and Improved Awning Roller, of which the following is a full, clear, and exact description.

This invention relates to improvements in means for raising and lowering awnings, and has particular reference to an awning roller.

An object of the invention is to facilitate the raising and lowering of an awning by providing means in connection with the awning roller which will effectively guide the awning as the same is raised and lowered and prevent the awning from coming in contact with the means utilized to accomplish such operations.

The above and other objects will appear more clearly from the following detail description, when taken in connection with the accompanying drawing, which illustrates a preferred embodiment of the inventive idea.

In the drawing—

Figure 1 is a fragmentary front elevation of the exterior of a window showing an awning in lowered position and the means for operating said awning;

Figure 2 is an enlarged fragmentary longitudinal section through a portion of the mechanism for operating the awning roller and showing the invention applied thereto; and

Figure 3 is an end elevation of the means shown in Figure 2.

Referring more particularly to the accompanying drawing, the numeral 4 indicates an awning which is designed to be wound upon the roller 5 and which has its lower edge connected to rods 6, only one of which is shown in the drawing, said rods being in turn pivoted to suitable plates 7 secured to the wall of the building adjacent the window, as is customary in constructions of this character. A vertically disposed shaft 8 has its lower end mounted in a housing 9 in which suitable gearing (not shown) of any desired character is arranged and which may be operated by a crank insertable into an opening 10 in the housing 9. The upper end of the shaft 8 carries a bevel gear 11, which meshes with a similar gear 12 having a stub shaft 13, one end of which is mounted in the housing 14 and the other end project-

ing into the adjacent end of the roller 5 and secured thereto in any suitable manner. The construction so far described is well known and forms no part of the present invention. The present invention contemplates the provision of a means in the nature of a shield 15, which is interposed between the roller 5 and the gearing for operating the same for the purpose of guiding the awning when the same is being raised and lowered and for preventing said awning from coming in contact with the gears 11 and 12, which would otherwise result in a mutilation of the awning. The shield 15 is formed of a single sheet of material, preferably circular in formation and having a central opening 16 for receiving the portion of the stub shaft 13 which projects into the end of the roller 5. The central portion of the shield 15 is secured to the rear face of the gear 12 by suitable fasteners 17. The portion of the plate forming the shield adjacent the periphery thereof is bent to provide an annular flange 18, which is of sufficient width to enclose the gear 12 within the shield and also overlap the portions of the gears 11 and 12 at the point where said gears intermesh.

From the foregoing description it will be apparent that when the awning is being raised and wound upon the roller 5, the same will be properly guided upon the roller by the shield 15, which will prevent the awning from extending beyond the adjacent end of the roller should an uneven winding of said awning occur. In this event the edge of the awning would engage the flange 18 and be diverted back onto the awning. The flange 18 also prevents the awning, in the case of an uneven winding thereof, from coming in contact with the gears 11 and 12 at points where the same intermesh thereby minimizing the possibility of the awning becoming torn or mutilated by said gearing.

What is claimed is:

In a device for raising and lowering awnings, an awning roller for receiving an awning, a shaft extending from one end of said roller, gears for operating said shaft to rotate said roller, and a shield consisting of a plate secured to one of said gears and having an opening for receiving said shaft, said plate being bent between its outer edge and the portion thereof forming the edge of said opening to provide an annular flange

disposed diagonally with respect to the remaining portion of the plate and to the axis of rotation of said shaft and being capable of diverting the awning back on to the roller should a portion of said awning come in contact with said flange during the raising or lowering of the awning, said

flange being also of a width sufficient to encircle the periphery of the gear to which said plate is secured and partially encircle the other gear which cooperates with the first named gear to prevent contact of the awning with said gears. 10

DAVID FROEHLICH.
